ELECTRIC SWITCH

William Dubilier, New York, N. Y.

Application January 19, 1939, Serial No. 251,746.

2 Claims. (Cl. 200—67)

This invention relates to electrical switches and more particularly relates to novel switch arrangements for switching electrical currents.

This invention relates to improvements of the general type of switch such as is for example disclosed in Patent No. 1,780,758. These switches interrupt substantially large currents upon relatively minute physical application of pressure or force and displacement. The switch actuating element of a switch of this type consists essentially of a spring which is tensioned or biased to give a material displacement of one section thereof upon a relatively small movement of a different section thereof.

In accordance with my present invention, I contemplate novel improvements in such switching devices for materially reducing arcing upon circuit interruption by the switch. Such arrangements permit a greater current interrupting rating for the switch as compared to the prior equivalent structures. In one form of the invention I employ multiple contacts to produce a series make-and-break contact arrangement to reduce the interruption voltage on any one set of contacts. In another form of the invention, a metallic spring element is incorporated between switch contacts to reduce the arcing to at least half the value. The multi-contact series make-and-break switch is also useful for more complex circuit arrangements than the prior switches of this class.

To further increase the current carrying capacity or rating of the switch, I provide novel heat conducting members specifically in the form of ventilating fins as part of or adjacent the current carrying members of the switch as will be hereinafter described. In another form, a spark extinguishing magnet is incorporated adjacent the arcing contacts.

In accordance with the present invention I also provide a switch of very simplified form which is inexpensive and rugged and may be manufactured with extremely small dimensions. In still another form I utilize the compact switch as a telegraph key which may be carried in the palm of one's hand and readily carried about on one's person. Very small pressures on the key are translated into forces through the switch to actuate larger current interrupting members.

It is accordingly among the objects of the present invention to provide novel electrical switching arrangements having relatively large current interrupting characteristics; which materially resist arcing and corrosion at the contacts, and with improved cooling arrangements

adjacent thereto; and a particular form which is extremely small in size and inexpensive to construct.

A further object of the invention is to provide a novel compact telegraph key operable with small displacements.

These and further objects of the present invention will become apparent in the following description taken in connection with the drawings, in which:

Figure 1 is a perspective illustration of the exterior of a switch according to the present invention.

Figure 2 is a longitudinal cross-sectional view through the switch taken along the line 2—2 of Figure 1.

Figure 3 is a horizontal sectional view through the switch taken along the line 3—3 of Figure 2.

Figure 4 is a vertical cross-sectional view through the switch taken along the line 4—4 of Figure 2.

Figure 5 is a bottom view of the above switch.

Figures 6, 6A and 6B are modified arrangements for the armature contacting member corresponding to the form of Figure 3.

Figure 7 is a schematic electrical diagram of a general circuit arrangement for the multi-contact switch.

Figure 8 is a longitudinal sectional view through a modified form of the switch arranged for materially increasing its current interrupting property.

Figures 9 and 10 respectively are vertical cross-sectional views taken along lines 9—9 and 10—10 of Figure 8.

Figure 11 is a perspective view of a modification of the invention in the form of a telegraph key.

Figure 12 is a fragmentary perspective view of a further form of the invention for increasing the current carrying capacity of the switch contacts by heat dissipation.

Figures 13 and 14 show another form of the invention for increasing the current carrying capacity of the spring member by heat conduction.

Figure 15 is a perspective view, partially broken away, of still another form of the invention for quenching sparking at the switch contacts.

Figure 16 is a perspective view of a compact and simplified form of the switch.

Figure 17 is a plan view of the switch of Figure 16.

Figure 18 is an end view of the switch shown in Figure 16.

Figure 19 is a longitudinal cross-sectional view taken along line 19-19 of Figure 17.

Figure 20 is an alternate arrangement corresponding to the embodiment of Figure 19.

Figure 21 is a telegraph key device constructed with the compact switch of Figure 16.

Figure 22 is a perspective view of a further form of the invention sealed for minimizing 10 sparking.

Figure 23 is a cross-sectional view taken along 23-23 of Figure 22.

Figure 24 is an enlarged perspective view of a portion of the spring armature of Figure 23.

Referring now to the figures, one form of the compact high current capacity switch is shown in perspective in Figure 1. The switch is encased in a composition housing. The switch proper is set into the enclosure 20 with a removable cover 21 to complete the housing. A screw 22 is arranged to maintain the cover 21 closed upon the housing 20. A push-button 23 projects above cover plate 21 and is adapted to actuate the spring member inside the switch housing as will be described.

The interior of the switch is shown in cross-section in Figure 2. Screw 22 has a nut 24 to keep cover 21 and housing 20 together. Posts 25 are molded within the composition housing 20 as inserts and carry one end of switch actuating member 26 by screws 27 threaded into the posts 25. The switch actuating member 26 is of the type disclosed in the Patent 1,780,758 hereinabove referred to and essentially comprises a spring member split longitudinally to form two legs 30 and slightly bowed together and secured at the free end by a movable contact 31 as shown in Figure 3. Other equivalent switch arm forms may be used.

A central hole 32 is made in member 26 in order that screw 22 may clear it. The free ends of legs 30 are slightly constricted by the attached movable contact 31 to form a bowed region at 33 of member 26. Region 33 is tensioned and otherwise biased due to the lateral constrictions of legs 30 in the manner described in the patent. When area 33 of member 26 is slightly depressed by push button 23, the normally downwardly extending free end 31 of the member is impelled upwards against effective stop 34. A slight displacement of push button 23 will cause a relatively large physical displacement of movable contact 31.

In accordance with the present invention I provide a plurality of series-break contacts co-operating with contacts 31. The contacts are arranged to extend from posts 35 and 36. Posts 35 and 36 are inserts molded in position in the composition housing 20 which may be "Bakelite" or the like. Electrical connections are made to posts 35 and 36 through appropriate lugs 37 and 38' as seen in the bottom view, Figure 5. One set of series-break contacts are mounted on lower posts 35 and are indicated at 40, 40. The upper series-break contacts are indicated at 34, 34 mounted from the top of posts 36.

An important feature of the multi-contact series-break switch arrangement resides in the provision for insuring uniform contacting of the plurality of contacts when engaged. Each of the contacts 34 is supported from posts 36 by re-entrant spring members 38, as shown in Figures 2 and 3. Lower contact arms 40, 40 are similarly suspended from posts 35 by reentrant spring 75

elements 48. Thus any difficulty due to misalignment of the respective pairs of contacts with respect to the movable contacts 31 are immediately compensated for by the individual spring action on the contacts. The effective position of the contacts 34 when pressed by movable contact 31 is such as to effectively stop the movable contact before it reaches its dead center position as already explained.

The contact areas of elements 31, 34 and 40 are preferably silver clad to resist corrosion. The base of these members may be copper or of other suitable material. The upper contacts 34, 34 are arranged at a position to properly arrest movable contact 31 in its upward excursion. The free end 31 of member 26 is prevented from reaching or passing its dead center position when button 23 is depressed, by means of the effective stop contacts 34, 34 and correspond to the position of the stop member 12 shown in the patent referred to. A spring 28 is arranged beneath spring actuating member 26 adjacent the sensitive area 33 thereof as shown in Figure 2. A set screw 29 is threaded in the base of housing 24 and is arranged for adjusting the pressure of spring 28 against member 26. This adjustment serves to properly bias the bowed member 26 into its normal contacting position against the lower contacts 40, 40 as shown in the diagram.

Movable contact 31 normally presses against the lower contacts 40, 40 and establishes a series electrical connection therebetween. When button 23 is depressed downwards against sensitive region 33, movable contact 31 rises from the lower contacts breaking the circuit therebetween and establishing a series circuit between upper contacts 34, 34 while the button is in the depressed position. When push-button 23 is released, the upper circuit 34, 34 is broken and the lower one 40, 40 is reestablished. A further circuit may be incorporated by including spring actuating member 26. Member 26 may be of spring steel but preferably of beryllium copper, or phosphor bronze to provide springiness and electrical conductivity. Electrical connection to member 26 including movable contact 31 is effective through one of the supporting metallic posts 25 at the bottom of which is secured a connecting lug 41. The base 42 of the switch contains projections 43 and 44 molded therein to serve as feet for the unit, so that it may be placed upon a base without interfering with the electrical connections thereto.

Figure 6 shows a modified arrangement for insuring proper contact between the movable contact element and the multi-contacts. Member 26a corresponds to member 26 in the previous form and movable contact bar 31a to corresponding bar 31 which bows together the respective legs 30a of the member. The contact bars 38 supported on the top of contact posts 36 in this form may be substantially rigid members in place of the spring supported contacts 34 of the previously described form. The legs 30a extend beyond the clamping bar 31a to form projecting contact portions 39, 39. Projections 39 are springy and adjust themselves for suitable pressure contact against the more rigid contact bars 38a. Suitable non-corrosive coatings are applied onto the contacting portions of projections 39 and bars 38a. The inherent springiness of the projections insures proper electrical connection between members 26a and the connections to post 36, 36.

Figures 6a and 6b are modified arrangements

for the switch of the invention to provide double-pole switching. The spring member 126 has two legs 130-138 bowed together by an insulation movable cross bar 131 to form the biased sensitive region shown in dotted at 133. Member 126 is equivalent to member 26 hereinabove referred to in the other modifications and is utilized in the switch in a similar manner. The distinction of the form of Figure 6a is that two independent contact members 132-133 are secured to a projecting end of the composition or insulation cross bar 131. Cross bar 131 may be "Bakelite" or other composition material arranged to bow legs 130 of member 126 in a manner now understood, as well as insulatingly support contact member 132-133 thereon. Electrical connections 134 are used to conduct current to contact member 132. Sufficient space is provided between opposed ends of legs 130 and contacts 132 to insure sufficient electrical insulation therebetween.

Another form for the double-pole switch of the invention is shown in Figure 6b. Here two separate legs 140-148 are used to form the spring flexed member. In this case, an insulation sheet or layer 141 is secured by suitable means at points 142 near one end of the spring leaf legs 140. At the opposite end an insulation cross bar 143 is pinned at 144-144 bowing the structure at insulation layer 141 to form a biased, sensitive region shown in dotted at 146 thereon. In the form of Figure 6b the sensitive region of the spring member is formed from the springing of an insulation layer 141 which may be "Bakelite," mica or other suitable material. At the left end of legs 140, movable contact lugs 146 are provided to coat with contact posts for electrical connection.

Terminal connections 147 are made to spring leafs 140 for conducting current therethrough. It is to be understood that the double-pole spring members of Figures 6a and 6b are mounted within a switch unit such as illustrated in connection with Figures 1-6, coacting with fixed contact posts for either single-throw or double-throw action as will be understood by those skilled in the art.

In applications where the switch may be subjected to much higher than normal ambient temperatures, I employ a switching member constructed of a spring material which maintains its springy qualities at elevated temperatures. Thus, while the material for the spring member 26 for normal temperature operation may be sheet copper, phosphor bronze, beryllium copper or the like; for uses where a much higher temperature than normal is encountered, I employ a flat spring material of a special alloy known in the trade as "Tophet C." This alloy comprises essentially 60% nickel, 15% chromium and about 15% iron, which is tempered to maintain its spring like qualities at high temperatures. Such metal has heretofore been employed as an electrical resistance wire. But by using it for example as the material for the switching member 126 in Figure 6a, as a flat spring instead of a wire I achieve this new result. The spring member 126 is mechanically constructed as heretofore with the slotted portion and bowed region as described. I prefer to employ the composition bowing movable contact carrying member as shown in the modification of Figure 6a to avoid passage of the electrical current through the spring member which, with the "Tophet C" metal, is of high resistance. Electrical connections are made to the contacts supported by the composition member.

The schematic electrical arrangement employing the multi-contact switch disclosed in connection with Figures 1 to 6 is shown illustrative in one of a number of methods of uses in Figure 7. 5 When movable contact 31 is in the lower position, shorting series contacts 40a, 40 circuit A is energized completing the electrical circuit through lower element or translating device 45 or its equivalent from the battery or source of energy 46. At the same time, circuit D formed by the movable contact member 31 and contact 60a is completed to energize the device 47 from the generator 48 in circuit therewith. When armature 31 is actuated to the upper position, circuits 10 A and D are broken and circuits B and C are completed. Circuit B includes load element 50 and source of energy 51 in circuit across contacts 34a and 34. Circuit C includes load device 52, generator or alternator 48, contact 54a, and armature 31. Figure 7 has been included to illustrate general circuit possibilities of the multi-contact switch of the invention. It is to be understood that the load devices shown by the rectangles may be any electrical device and the sources of energy likewise be any circuit energizer. Various other arrangements will suggest themselves to those skilled in the art.

In Figure 7, movable contact member 31 represents the short-circuiting element of member 26, and corresponds to the movable contact 31 of Figures 2 to 5 as well as projections 39, 39 of Figure 6 as will be understood. An important feature of the invention is the circuit interrupting action such as for the A and B circuits, accomplished in series-break relation between two contacts and the movable contact member. Sparking between any one contact and the movable contact is reduced to below half as compared to the sparking occurring in the prior equivalent switching arrangements for a given current. The current carrying capacity of a given switch construction is accordingly substantially increased as to its current interrupting rating. Circuits C and D represent the single contact interruption arrangement and illustrates how the switch may be used in this manner as well as or in conjunction with the series-break arrangement.

Figures 8, 9 and 10 illustrate another form of the invention particularly constructed to minimize sparking at the contacts and thereby increase the current interrupting rating of the switch unit. Figure 8 is a vertical cross-sectional view showing the arrangement of the respective parts. The form is essentially similar to that shown in Figure 2 with the addition of an auxiliary contact element 55 interposed between movable contact 31 and lower contact 56. A single set of contacts is used for each side; contact 56 being the lower one extending from post 57, and contact 58 being the upper one extending from post 59. Figures 10 and 11 more clearly show the arrangement of the respective contact elements.

Auxiliary spring 55 is interposed in the current interrupting circuit between the lower contact 56 and the movable contact 31. A set screw 60 passing through an opening in member 26 abuts an intermediate portion of spring 55 for defining its upper position with respect to contact 56. Set screw 55 is threaded within cover plate 21 as shown. The spark reduction action of member 55 is accomplished as follows:

When push button 23 is in its normal released position, an electrical circuit is established between terminal 41 of the movable contact, termi-

nal 61 of the lower contact 56, through movable contact 31, spring member 55 and contact 58 in pressure contact relationship. When push button 23 is depressed against the sensitive region of member 26, movable contact 31 snaps up to the position illustrated in Figure 8. As movable contact 31 moves upwards, spring 55 which is biased in the upward direction follows upwards with it. The circuit is first interrupted by the member 55 and contact 58 causing a sparking condition therebetween when the current is sufficiently large. However, the upward movement of contact 58 is limited by stop 60 to the illustrated position. Thus movable contact 31 travels further upwards and separates from member 55. A spark condition is produced between member 55 and movable contact 31. The intensity of the spark at any part in this arrangement is substantially less than the spark which would occur between movable contact 31 and contact 56 if member 55 were absent. Thus, for a given spark enduring capacity of the switch contacts, at least twice the current capacity of equivalent prior switches may be endured.

The contacting areas are coated with a corrosion resisting metal layer such as silver or a suitable alloy. The illustrated current breaking capacity between upper contact 58 and the movable contact 31 is less than that between the movable contact, spring member 55 and lower contact 58 as will now be evident. Accordingly, the circuit including upper contact 58 may be used for a minor current function in the circuit. It is to be understood that spark reducing spring member 55 may be positioned between movable contact 31 and the upper contact 58 in place of the illustrated position, or such additional arrangement may be used together with the illustrated member 55 to quench or reduce sparking for both contact sets 56 and 58 to armature.

A novel modification of the switch of the invention is illustrated in Figure 11 and encompasses a telegraph key. The switch included in housing 61 is the type disclosed in the patent hereinabove referred to, as generally illustrated in Figures 1 to 10. A spring actuating element corresponding to element 26 is located within casing 61 and is actuated by push button 62 at the sensitive region thereof corresponding to region 33 indicated in Figure 3. A small displacement of push button 62 of the order of a thousandth of an inch will cause a marked displacement of movable contact 31 to actuate the electrical contacts in the circuit.

A manually operable button or knob 63 is shown attached to a leaf spring 64 secured at 65 to the top of switch 61. Spring 64 passes over push-button 62. Spring 64 extends beyond the side of the housing 61. Knob 63 is attached to the free extending end of spring 64. Relatively small pressure and movement of button 63 causes large displacements of the internal spring member 26 (not seen in Figure 11) which is capable of interrupting relatively large current values for the circuit without sparking or corrosion. The telegraph key is readily manipulated without tiring by the operator. The extended end of spring 64 permits the operator to move button 63 even beyond the required amount, serving as a keying shock absorber. The springiness in spring 64 makes the actual displacement of button 63 non-critical as will now be evident, without interfering with the switching action of the switch contained in 61.

Figures 12, 13 and 14 are modified forms of the switch for carrying even greater current values with provisions for rapidly conducting away heat generated at the terminals, for cooling. Figure 12 shows the terminal contact posts 70 and 71 arranged opposite movable contact 72 carried at the end of fixed member 73. Member 73 is mounted on a post 74 supported in the housing not shown. Dotted region 75 corresponds to the sensitive area of actuation for the spring member 73 in the manner already described.

Contacts 70 and 71 are in the form of corrugations providing ventilating or heat conducting fins. The contacting regions 76 and 77 of the respective elements 70 and 71 are flat along an appreciable width for providing the necessary current contacting area. The vertical fins of contact elements 70 and 71 conduct heat away from the current contacting region and lower the temperature in the switch contacting areas. This arrangement greatly increases the current carrying and interrupting rating of the unit.

Figure 13 is a fragmentary end view of another form for cooling the switch of the invention to increase its current rating. Switch member 73' corresponds to the spring switch 73 of Figure 12 and is arranged to carry substantial current. To preserve the springiness of the member and provide proper operation thereof under high current values, cooling fins 80 and 81 are arranged on opposite sides of member 73' longitudinally along the length thereof and positioned as close thereto as practicable to permit proper up and down movement thereof. Corrugated elements 80 and 81 are of sheet material and arranged to give a large heat conducting area for maintaining the region adjacent the surface of member 73 cool. They are attached to enclosure 82. A push button 85 is arranged to press against the sensitive region of member 73' in the manner already described and projects through the upper fin as shown. Vents 86 are provided in the housing 82 adjacent the cooling fins 80 and 81 to provide proper circulation therefor.

A further form of the invention for minimizing and extinguishing sparking is illustrated in Figure 15. A permanent horseshoe magnet 90 is arranged with its poles 91, 91 adjacent the switching region including contacts 92-93 and movable contact member 94. The magnetic field of magnet 90 passes across the gaps of the switching members. The magnet is encased in the housing base 95 which supports the switching member as well. The switching element 96 corresponds to element 73 and 26 of the above modifications, arranged for actuation with small displacement and pressure of push-button 97. Magnet 90 is of the type having high permanent magnetism characteristics, to effect a strong magnetic field across the sparking gaps without materially increasing the volume of the switch. Magnet 90 is imbedded in a suitable recess provided in base 95 of the housing.

Figures 16 to 20 illustrate a form of the invention designed for very small and compact size, with a minimum of parts for inexpensiveness and ruggedness. A switch of this character, as illustrated in Figure 16, may be constructed with dimensions of the order of an inch to one and a half inches in length and about one-half inch in width and only about three-sixteenths of an inch in height. Figure 16 is a perspective view of the switch unit enclosed in casing 100 with connection lugs 101 and 102 projecting at opposite ends thereof. A grooved region 103 is ar-

ranged centrally of the molded housing 100 to provide a clamp for securing the unit to a base.

Figures 17 and 18 are respective plan and end views of the novel compact switch. The switch essentially comprises a cast or molded enclosure 100 which may be of ceramic, "Bakelite" or other similar insulation or composition material. Enclosure 100 contains a cavity for containing the switch parts and has opposed longitudinal legs 104 for supporting the unit on a base. As seen in cross-sectional views, Figures 19 and 20, rivets 106 and 107 are arranged to secure switch parts against the housing 100. Contact 102 is secured between housing 100 and actuation spring member 110. Electrical connection is accordingly afforded between electrical contact 102 and the spring member 110. Spring member 110 corresponds to member 26 in the previous embodiments and is properly bowed or biased in the manner previously referred to, to provide a sensitive region cooperating with push-button 111 for actuating movable contact 112 thereof into a material displacement. For a fireproof construction I employ a ceramic for the casing and ceramic or mica for other insulation layers.

Connection lug 101 is properly spaced from inside face 115 of casing 100 by an insulation spacer or block 116. Lug 101 is secured to casing 100 by rivet 106 with block 116 held therebetween. An extension 101' of lug 101 is arranged to contact with displaceable movable contact 112 for make-and-break electrical circuit action. An insulation layer 117, such as stiff paper, a "Bakelite" sheet, or the like, is secured with rivets 108-107 to provide a bottom protective covering for the switch elements. A spacer 118 insures proper room between displaceable member 110 and strip 117.

The switch of Figure 19 is a normal-make type. The same components may be used to form a normal-break switch as illustrated in Figure 20. The difference in construction comprises in reversing the position of contact lug 101 and block 116, placing extension 101' of the lug adjacent face 115 of casing 100, properly spaced from movable contact 112 to establish electrical connection therewith when it is displaced upwards by pressure from button 111. The novel interchangeability of switch construction with great simplicity of arrangement and form are important features of this invention.

Figure 21 illustrates a useful embodiment employing the simplified, compact, light-weight switch of Figures 16 to 20 as a minute but effective telegraph key. A flexible leaf spring 120 is secured at one end 121 to the top of switch casing 100. The free end 125 of spring 120 is longer than the switch and extends substantially beyond. The intermediate portion of spring 120 is spaced above switch 100 and is arranged to contact with push-button 111. As shown by the dotted position, spring lever 125 is not limited in its excursion, and presents smooth keying without jar or strain. Lever 120 operates on button 111 which in turn depresses the sensitive biased region of switch member 110 to in turn displace movable contact 112 with respect to the electrical contacts of the switch. One or two connection members corresponding to extensions 101' of Figures 19 and 20 may be arranged to coact with movable contact 112, according to the switching requirements. The elastic response of the spring member 110 and lever 120 is proportioned to secure proper keying speed as will be evident to those skilled in the art.

A further important modification of the invention is illustrated in Figures 22 to 24 where a switch member including the contacts is sealed in a structure which contains an inert gas to eliminate deleterious effects of any possible sparking action. The casing 150 of the switch may be of metal for rigidity and strength, sealed at the ends by caps 151 through a welding or other suitable joint connection. A push button 152 is arranged on one face of housing 150 for actuating the sensitive switch within the unit and yet permitting an air-tight seal therefor. Push button 153 consists of a diaphragm or bellows 153 held in position by a retaining ring 154 secured to the casing. Connections 155 and 156 are passed through openings in caps 151 for establishing suitable electrical connections to the contained switch. The ends 157 are sealed about the wires with suitable sealing material preferably of an insulation material such as pitch, wax or the like, to prevent moisture or air from entering. It is feasible to employ only one opening for all terminal connections in place of the two shown.

Figure 23 shows a preferred arrangement for this type of switch corresponding to a cross-sectional view along 23-23 of Figure 22. The housing 150 is of metal. The spring switch device, constructed integrally with insulation structure 160, is similar to the hereinabove units described except in that ribbed regions 161 are provided longitudinally of the member to coact with channels 162 integral with casing 150. The rib-channel arrangement 161-162 rigidly holds switch unit 100 within the enclosure 150.

The diaphragm push button 152 comprises the diaphragm 153 having a flexed annular region 158 near its periphery. The edge of diaphragm 153 rests in a recessed portion at 159 of the housing. The retaining ring 154 is screwed in proper threading in housing 150 adjacent the edge of diaphragm 153. This type of push button permits sealing of the unit from external space and yet permits a sensitive push button arrangement for actuating the spring member 165 within the switch.

Spring member 105 is similar to the springs 26 and 78 of the hereinabove described modifications and is flexed or bowed to have a sensitive region at 166. In the illustrated form, a rod 167 is attached to the sensitive region 166 and projects through the structure 160 beneath the central portion of push button 152. A projection 168 is secured to diaphragm 153 opposite and closely spaced from rod 167 as shown in Figure 23. A small pressure and/or displacement upon button 152 will communicate corresponding action on rod 167 to the sensitive region 166 of the spring member 165 and operate it in a manner already described for switching the currents flowing in the switch. It is to be understood that rod 167 need not be attached to member 165 but rather project integrally with portion 168 of the button down to the sensitive region of member 165 in a manner of the previous push buttons described.

The joints of the enclosure for the switch are sealed for air-tightness. Thus, the ends of push button 152 including the retaining and sealing ring 154 are treated with varnish, "Glyptol" or other suitable material for sealing this region of the switch casing 150. As already described, the joints between caps 151 and casing 150 are welded for air-tightness; the openings through caps 151 for terminal wires 155 and 156 are also properly sealed. After the switch is assembled

for use in the manner described and illustrated, sparking within the switch will very quickly burn up all the available oxygen therein, leaving wholly inert gas in the sealed switch. The deleterious effects on the materials due to arcing are thus greatly minimized. A further advantage is that the switch may be employed in dusty, humid or wet places without affecting its electrical characteristics.

Although I have illustrated several embodiments of preferred forms of the present invention, it is to be understood that modified arrangements and constructions are feasible falling within the broader spirit and scope of the invention. Accordingly I do not intend to be limited except by the following claims.

I claim:

1. In a switch of the character described, the combination of a biased leaf spring having a conductive element at one end, a ceramic casing having, crosswise, a U-shaped section and lengthwise an upstanding end wall at one end providing a surface for positioning the other end of the leaf spring to be clamped, a contact plate, arranged adjacent the conductive end of the spring for making electrical contact therewith,

5 said plate being mounted at the other lengthwise end of said casing, and an insulating cover fitted lengthwise within said casing covering the open side thereof and having clamping elements at either end, clamping at one end said leaf spring and at the other end said contact plate.

2. In a switch of the character described, the combination of a biased leaf spring having a conductive element at one end, a ceramic casing having, crosswise, a U-shaped section and lengthwise an upstanding end wall at one end providing a surface for positioning the other end of the leaf spring to be clamped, a connection lug having a contact portion arranged for electrical 10 coating with said conductive element and a spacer block for positioning the contact portion of said lug in circuit make or break position with respect to said conductive element, said contact portion and spacer both being mounted on the other lengthwise end of said casing and an insulating cover fitted lengthwise within said casing covering the open side thereof and having clamping elements at either end, clamping at one end said leaf spring and at the other end said contact plate and spacer.

WILLIAM DUBILIER.
